AMPLIFICATION CONTROL

Knox Charlton Black, Boonton, N. J., assignor,
by mesne assignments, to Radio Corporation of
America, New York, N. Y., a corporation of
Delaware

Application April 14, 1930, Serial No. 444,246

37 Claims. (Cl. 250—20)

This invention relates to vacuum tube amplifiers and particularly to methods of and apparatus for controlling the amplification of or transmission through the amplifier.

5 It is the common practice to control the amplification of a vacuum tube by adjusting the operating potential upon one of the elements, i. e., by varying the direct current potential existing between that element and the cathode. I have found
10 that a greater flexibility of amplification may be attained and, in general, with less variation of amplification-control voltages, when the operating potentials upon a plurality of the tube elements are simultaneously varied. The control voltages
15 may be varied at the same or different rates and in the same or opposite sense, in accordance with the shape of the amplification characteristic which is desired for any particular amplifier.

Objects of the invention are to provide a vacuum tube amplifier in which the control of amplification is effected by the simultaneous adjustment of the operating potentials applied to a plurality of the tube elements. More particularly, an object is to provide, in an amplifier of the type employing a tube having a plurality of grid elements, an amplification control in which the control grid bias and the operating potential upon another tube element are simultaneously adjusted.

30 These and other objects of the invention will be apparent from the following description, when taken with the accompanying drawings in which:

Fig. 1 is a diagram of an amplifier circuit embodying the invention,

35 Figs. 2 and 3 are characteristic curves showing the relationship, for different parts of the tube of Fig. 1, between amplification-control voltages and plate current,

40 Fig. 4 is a family of curves showing the relation between total plate current and control grid voltage for different values of the auxiliary grid voltage, and

Fig. 5 is a circuit diagram of another embodiment of the invention.

45 In Fig. 1, the invention is illustrated in connection with an amplifier tube T which has a cathode C, control grid G², screen grid G³, anode P and auxiliary grid G¹. The general arrangement of the tube elements may conform to that of commercial tetrode tubes having coaxial cylindrical elements.

The control grid G² comprises a winding which is not of uniform pitch throughout its length, the section 1 being of substantially coarser pitch than
50 the section 2. The auxiliary grid G¹ is not co-

extensive with control grid G² but extends between only the portion 1 of grid G² and the cathode C.

The input circuit 3 is connected through a blocking condenser 4 to the control grid and cathode, the grid bias voltage being derived from a source of current 5 through potentiometer 6 and the customary grid resistance 7. The auxiliary grid G¹ is connected to that terminal of resistance 7 which is spaced from the control grid G².
5

The direct current bias on the auxiliary grid is therefore the same as that on the control grid but, as regards signal potentials, the grid G¹ is maintained at the cathode potential by the bypass condenser 8. The screen grid and plate circuits may be of any desired form, being here shown as energized from a common battery 9.
10

The special construction of the control grid results in a tube which exhibits the general characteristics of a high mu tube at one range of operating voltages and the general characteristics of a low mu tube at another range of operating voltages. This type of tube is disclosed and claimed by H. A. Snow in his application Serial No. 437,225, filed March 19, 1930. The control of plate current by section 2 of grid G² is, neglecting fringing, a function of the control grid bias and is represented graphically by curve A of Fig. 2. For the section 1 of control grid G², the plate current is determined by the bias voltages
20

on both the control grid G² and the auxiliary grid G¹. Due to the coarser spacing of the section 1 of control grid G², this portion of the tube functions as a low mu tube and, in general, the control grid bias-plate current curves are much flatter than the corresponding curve for the portion of the tube in which the section 2 of grid G² is located.
25

In Fig. 3, the family of curves B to F show the relation of plate current to control grid bias on section 1 of grid G², for different values of the auxiliary grid bias, i. e., for auxiliary grid bias voltages of 2, 5, 8, 11 and 14 volts negative, respectively. The total plate current is equal to the sum of the effects of the bias voltages upon the sections of the control grid, and its relation to control grid bias voltage may be represented by combining the characteristics of Figs. 2 and 3. In Fig. 4, the curves B' to F' give the relationship between total plate current and control grid bias voltage for the respective fixed auxiliary grid bias voltages noted above.
30

When, as by means of the circuit of Fig. 1, the control grid and auxiliary grid are subjected to the same amplification control potential, the
35

graph of the operating points may be plotted as dotted line H upon the curves of Fig. 4.

Since the signal voltage is effective only upon the control grid, and not upon the auxiliary grid, 5 the path of operation for the signal is not the dotted line H but the full line B', C', etc., drawn through the line H at its intersection with the ordinate corresponding to the direct current potential upon the two grids.

10 Advantages obtained by this use of adjusted voltages on two tube elements will be evident from an examination of the curves of Fig. 4. It is obvious that a wide range of amplification control corresponds to a relatively small variation of 15 control voltage. If the bias on the auxiliary grid remained fixed, or if the auxiliary grid were omitted, it would be necessary to use a much higher negative voltage on the control grid to reduce the amplification to a value corresponding, for 20 example, to -14 volts on the grids G¹ and G², i. e., to operation of the tube at the point of intersection of curves H and F'. Furthermore, by an appropriate design of the tube, the distortion may be reduced when the signal is applied to but 25 one grid and two bias voltages are controlled. This follows from the fact that the operating point of the tube travels along dotted line H as the control voltage is varied, but the amplification is determined by the full line passing through the operating point. Although the dotted line may be 30 steep and curving rapidly, distortion will not occur if the full lines, adjacent their respective intersections with line H, are not too seriously curved.

35 The invention is not restricted to the manual control or to the special type of tube shown in Fig. 1.

In Fig. 5, I have illustrated the invention as applied to the automatic control of the transmission or volume level in an amplifier-demodulator 40 system.

An appropriate input system, such as a tuned circuit 10 impresses the incoming carrier wave signal between the control grid G² and the cathode C of an amplifier tube 11, and the amplified 45 signal is passed, by a tuned coupling circuit 12 to the demodulator 13, which may be a diode. The output circuit of the demodulator preferably includes the usual radio frequency choke 14 and by-pass condenser 15, the rectified output voltage 50 being developed across a resistance 16, and terminals 17, 18 across which an audio amplifier or other appropriate load circuit may be connected.

The rectified carrier voltage developed across the output resistance 16 is employed to effect an 55 automatic control of the output level of the system. The direct current bias of grid G² is determined indirectly by the bias voltage on grid G¹ and the potential difference between the two grids. The cathode of the amplifier 11 is grounded 60 for direct current and radio frequencies, and the detector circuit is grounded through condenser 19 for radio frequencies.

The tube 11 is provided with a space-charge grid G¹ and, if desired, with a screen grid G³. The bias upon the grid G¹ is determined in part by the relatively fixed potential of that adjustable portion of the plate supply 21 that is impressed, through adjustable tap 22, upon the plate of a direct current amplifier 23, and in part by that 70 portion of the rectified carrier voltage across output resistance 16 which is impressed upon the direct current amplifier 23.

The cathode of amplifier 23 is connected, through a battery 24, to an adjustable tap 25 75 on resistance 16 and the grid is connected to the

anode terminal of the resistance. The grid G¹ of tube 11 is connected to the cathode of the amplifier 23 and is by-passed to its own cathode by condenser 26 to eliminate audio frequency components.

Since the more positive rectified carrier voltage is at the terminal of resistance 16 which leads to the cathode of the diode 13, it is apparent that the grid of the direct current amplifier 23 becomes more negative as the carrier voltage increases. The positive direct current bias on grid G¹ is therefore reduced as the signal strength increases.

The direct current path between the control grid G² and grid G¹ may be traced through the 15 grid resistance 27, (by-passed for audio frequency components by condenser 28), then through battery 29, the portion of resistance 16 which is included between taps 30 and 25, and battery 24 to the grid G¹. In the absence of a signal, the 20 potential of control grid G² is more negative than that of G¹ by the sum of the potentials of batteries 28 and 29. The effective bias on grid G² is equal to the difference between this potential drop and the bias on grid G¹. When a signal is 25 received, the effective bias on control grid G² is decreased, i. e., is made less negative by the drop of rectified carrier voltage between taps 25 and 30 on resistance 16.

The direct current potentials on grids G¹ and 30 G² are so adjusted, by choice of the relatively fixed components of the bias-voltages, that the negative bias on the control grid G² and the positive potential on the space charge grid G¹ will give high amplification for small signal voltages. 35

As the signal voltages increase, the rectified carrier voltage developed across resistance 16 operates to make the control grid bias voltage less negative and to reduce the positive potential on the space charge grid. The lowered voltage on 40 the space charge grid reduces the amplification while the decreased bias on the control grid may have but little effect upon the amplification. By a suitable positioning of the adjustable taps 25, 30, the relative effects of the two amplification 45 controlling voltages may be proportioned in any desired manner and advantage may be taken of the amplification change effected by the altered control grid bias but, in general, this will be of minor importance. The decreased control grid 50 bias is of major importance for its effect upon the plate current. The reduction of space charge grid voltage, to effect volume control, would be accompanied by a marked increase in plate current if the control grid bias remained constant, 55 and this tendency towards an increased flow of plate current may be reduced by decreasing the control grid bias.

The above examples are illustrative of my invention and it is to be understood that, in other 60 circuit arrangements and with other tube constructions, the advantages noted above and/or other advantages may be obtained by the simultaneous adjustment of the operating voltages applied to a plurality of tube elements.

I am aware of the fact that a change in the operating potential applied to one tube element may alter the effective potential between another tube element and the cathode. Such incidental 70 alteration of an operating potential upon a second tube element is not contemplated by the present invention which comprises the simultaneous adjustment, by a deliberate change of the applied direct current voltages, of the oper- 75

ating potentials upon two or more tube elements.

I claim:

1. In the operation of an amplifier circuit of the type including an audion having a plurality of grid elements, and means for establishing different direct current potentials upon the several elements, the method of controlling the amplification which comprises simultaneously adjusting the direct current potentials applied to at least two of said elements in accordance with the strength of signals applied to the amplifier.

2. The invention as set forth in the above claim 1, wherein the potentials upon said two of said elements are varied at different rates to control the amplification.

3. The invention as set forth in claim 1 wherein the potentials upon said two of said elements are varied in opposite sense.

4. The invention as set forth in claim 1 wherein the potentials upon said two of said elements are varied in opposite sense and at different rates.

5. In the operation of an amplifier tube of the type having a cathode, an anode, a control grid and a second grid, the method of controlling the amplification which comprises simultaneously adjusting the direct current potentials between the respective grids and the cathode in response to variations in the strength of signals applied to the amplifier.

30 6. In an amplifier circuit, an amplifier tube having a cathode, an anode, a control grid and a second grid, means for establishing direct current potentials between said cathode and each of the other tube elements, means for impressing a signal voltage between cathode and control grid, and means for simultaneously adjusting the direct current potentials upon said control grid and upon another tube element in response to variations in the strength of signals impressed on the amplifier.

40 7. The invention as set forth above in claim 6, wherein said potential adjusting means effects simultaneous adjustment of the direct current potentials upon the respective grids.

45 8. The combination with an electron discharge tube and circuit elements associated therewith to constitute an amplifier stage, said tube being provided with a cathode, anode, and a plurality of auxiliary tube elements, of adjustable means responsive to changes in the amplitude of signals impressed on said tube for simultaneously varying the operating potentials existing between the tube cathode and at least two of said plurality of the tube elements.

55 9. The combination with a vacuum tube having an anode, a cathode, a control grid and an additional grid disposed between the cathode and the control grid, of circuit elements cooperating with said tube to constitute the input and output circuits of an amplifier stage, means for varying the direct current potential between said control grid and said additional grid, means for varying the bias between one of said grids and said cathode, and means insuring the simultaneous operation of said voltage varying means.

60 10. In a carrier wave amplifier, the combination with a vacuum tube having a cathode, an anode and a plurality of grids, of means for impressing a carrier wave signal voltage between one of said grids and said cathode, means for rectifying the amplified output from said amplifier, and means for automatically adjusting the operating potentials applied to a plurality of said tube elements in accordance with the strength of the incoming signal.

11. The invention as set forth in the above claim 10, wherein said automatic adjusting means comprises a resistance in the output circuit of said rectifier, circ't elements for impressing between said amplifier cathode and one of said tube elements a direct current voltage proportional to the rectified carrier voltage across said resistance, and circuit elements including a direct current amplifier for impressing across two of said tube elements a direct current voltage proportional to said carrier voltage.

5 12. An amplifier circuit comprising an electron discharge tube provided with a cathode, anode, control grid, and auxiliary grid, said control grid being so constructed as to provide at least two electron streams flowing at different rates within the tube, means for maintaining said grids at different signal potentials, and additional means for simultaneously varying the direct current potentials of the grids.

15 13. An amplifier circuit comprising an electron discharge tube provided with a cathode, anode, control grid, and auxiliary grid disposed between the cathode and control grid, means for maintaining said grids at different signal potentials, and additional means for simultaneously varying the direct current potentials of the grids at different rates.

20 14. An amplifier circuit comprising an electron discharge tube provided with a cathode, anode, control grid, and auxiliary grid, said control grid being so constructed as to provide at least two electron streams flowing at different rates within the tube, means for maintaining said grids at different signal potentials, and additional means for simultaneously varying the direct current potentials of the grids in opposite sense.

25 15. An amplifier circuit comprising an electron discharge tube provided with a cathode, anode, control grid, and auxiliary grid disposed between the cathode and control grid, means for maintaining said grids at different signal potentials, and additional means for simultaneously varying the direct current potentials of the grids in opposite sense and at different rates.

30 16. An amplifier circuit comprising an electron discharge tube provided with a cathode, anode, control grid, and auxiliary grid, means for maintaining said grids at different signal potentials, and additional means for simultaneously varying the direct current potentials of the grids, said auxiliary grid extending between only a portion of the control grid and said cathode.

35 17. An amplifier circuit comprising an electron discharge tube provided with a cathode, anode, control grid, and auxiliary grid, said control grid being so constructed as to provide at least two electron streams flowing at different rates within the tube, means for maintaining said grids at different signal potentials, and additional means for simultaneously varying the direct current potentials of the grids, said auxiliary grid being positioned only in the path of one of said electron streams.

40 18. An amplifier circuit comprising an electron discharge tube provided with a cathode, anode, control grid, and auxiliary grid, said control grid being so constructed as to provide at least two electron streams flowing at different rates within the tube, means for maintaining said grids at different signal potentials, and additional means for simultaneously varying the direct current potentials of the grids, a tunable input circuit coupled to said control grid and cathode, and a

65

70

75

- blocking condenser between said input circuit and said control grid.
19. An amplifier circuit comprising an electron discharge tube provided with a cathode, anode, control grid, and auxiliary grid, said control grid being so constructed as to provide at least two electron streams flowing at different rates within the tube, means for maintaining said grids at different signal potentials, and additional means for simultaneously varying the direct current potentials of the grids, said additional means including a source of direct current, a resistor in shunt with said source, a resistor connected between said grids, and an adjustable connection between said last resistor and said shunt resistor.
20. In combination with a multi-electrode tube including a cathode, anode and control grid, another electrode between the cathode and control grid, a signal input circuit connected between the control grid and cathode, an output circuit connected between the anode and cathode, means connected to the control grid for controlling the direct current potential thereof, and additional means connecting said first means and said other electrode of said tube for controlling the direct current potential of said last electrode.
21. In combination with a multi-electrode tube including a cathode, anode, auxiliary grid and control grid, the auxiliary grid being a space charge grid between the cathode and control grid, a signal input circuit connected between the control grid and cathode, an output circuit connected between the anode and cathode, means connected to the control grid for controlling the direct current potential thereof, and additional means connecting said first means and said auxiliary electrode for controlling the direct current potential of said last electrode.
22. In combination with a multi-electrode tube including a cathode, anode and control grid, said tube being constructed to have a variable mu characteristic, a signal input circuit connected between the control grid and cathode, an output circuit connected between the anode and cathode, means connected to the control grid for controlling the direct current potential thereof, and additional means connecting said first means and another electrode of said tube for controlling the direct current potential of said last electrode.
23. In combination with a multi-electrode tube including a cathode, anode and control grid, a second positive grid between the cathode and control grid, a signal input circuit connected between the control grid and cathode, an output circuit connected between the anode and cathode, means including an adjustable potential source connected to the control grid for controlling the direct current potential thereof, and additional means connecting said first means and the second grid of said tube for controlling the direct current potential of said second grid.
24. In combination with a multi-electrode tube including a cathode, anode and control grid, a signal input circuit connected between the control grid and cathode, an output circuit connected between the anode and cathode, a rectifier coupled to the output circuit, means connected to the control grid and the rectifier output for controlling the direct current potential thereof, and additional means connecting said first means and another electrode of said tube for controlling the direct current potential of said last electrode.
25. In combination with a multi-electrode tube including a cathode, anode and control grid, a signal input circuit connected between the control grid and cathode, an output circuit connected between the anode and cathode, means connected to the control grid for controlling the direct current potential thereof, and additional means connecting said first means and another electrode of said tube for controlling the direct current potential of said last electrode.
26. In combination with an amplifier circuit including a tube provided with a cathode, control electrode, and a plurality of positive electrodes, an automatic gain control circuit comprising a rectifier having its input arranged to receive energy from said amplifier output, means for connecting the control electrode of the amplifier tube to the rectifier output, and means for connecting at least one of said positive electrodes to the rectifier output.
27. In combination with an amplifier circuit including a tube provided with a cathode, control electrode, and a plurality of positive electrodes, an automatic gain control circuit comprising a rectifier having its input arranged to receive energy from said amplifier output, means for connecting the control electrode of the amplifier tube to the rectifier output, means for connecting at least one of said positive electrodes to the rectifier output, and an electron discharge tube connected between said one positive electrode, the amplifier output and the rectifier output.
28. In combination with a radio receiver including an amplifier circuit provided with a multi-electrode tube and a detector circuit, an automatic amplifier gain control arrangement consisting of connections between at least two electrodes of said tube disposed in the electron stream from the cathode and the detector circuit output whereby the potentials of the two electrodes with respect to the cathode may be varied.
29. In combination with a radio receiver including an amplifier circuit provided with a multi-electrode tube and a diode detector circuit, an automatic amplifier gain control arrangement consisting of connections between at least two electrodes of said tube disposed in the electron stream from the cathode and the detector circuit output whereby the potentials of the two electrodes with respect to the cathode may be varied.
30. In combination with a radio receiver including an amplifier circuit provided with a multi-electrode tube and a detector circuit, an automatic amplifier gain control arrangement consisting of independent, adjustable connections between at least two electrodes of said tube disposed in the electron stream from the cathode and the detector circuit output whereby the potentials of the two electrodes with respect to the cathode may be varied.
31. In an electrical wave amplifier system, an amplifier tube, including a cathode, an anode, a control grid electrode of variable mesh, a screen grid between the anode and grid, and an auxiliary cathode, an output circuit between the anode and cathode, a wave input circuit between the control grid and cathode, and means for regulating the direct current potentials of said two grids with respect to said cathode.
32. In combination with a wave amplifier provided with a cathode and a plurality of cold electrodes, means for maintaining certain of the cold electrodes at a positive potential, a wave demodulator for producing a direct current po-

tential to regulate the gain of said amplifier, and means for connecting the demodulator to at least two of said cold electrodes whereby the potentials of the latter with respect to the cathode 5 may be varied.

33. In combination with a wave amplifier provided with a cathode and a plurality of cold electrodes, means for maintaining certain of the cold electrodes at a positive potential, a wave demodulator for producing a direct current potential to regulate the gain of said amplifier, means for connecting the demodulator to at least two of said cold electrodes whereby the potentials of the latter with respect to the cathode 10 may be varied, and at least one of the two cold electrodes being at said positive potential.

34. In a signal modulated carrier wave receiving system, a tube including a cathode, an anode, a signal grid and a special gain control electrode disposed between the cathode and signal grid, a tuned signal wave input circuit connected solely between the signal grid and cathode, said signal grid being at a predetermined negative direct current potential with respect to said 15 cathode and gain control electrode, a signal wave

rectifier circuit adapted to produce a direct current voltage whose magnitude varies in response to variations in amplitude of received carrier waves, and connections between said gain control electrode and the rectifier circuit for applying said voltage to the gain control electrode in such a sense that the electrode voltage varies in a negative direction with respect to the cathode as the signal waves impressed on said input circuit increase in amplitude. 10

35. In a system, as defined in claim 34, said rectifier circuit including a diode, said tube including a positive screen grid adjacent the signal grid.

36. In a system, as defined in claim 34, said rectifier circuit being coupled to the anode circuit of said tube, and a wide range of gain control of said tube corresponding to a relatively small variation of rectifier direct current voltage. 15

37. In a system, as defined in claim 34, a connection between the said signal grid and rectifier circuit for regulating the magnitude of the negative potential of said signal grid in response to said carrier wave amplitude variations. 20

KNOX CHARLTON BLACK. 25
